The ornamental design for a shoe upper with lacing arrangement, as shown and described.

DESCRIPTION

FIG. 1 is a front perspective view of a shoe upper with lacing arrangement showing my new design;

FIG. 2 is a side view thereof;

FIG. 3 is a second side view thereof; and,

FIG. 4 is a top view thereof.

The broken lines immediately adjacent to the shaded area represent unclaimed boundaries of the design. The broken lines showing the holes for the lace and lace holders are for environmental purposes only and form no part of the claimed design. The broken lines showing the remainder of the shoe are for environmental purposes only and form no part of the claimed design.
